SCRAPER

Henry C. French, Milwaukee, Wis., assignor to
The Heil Co., Milwaukee, Wis., a corporation of
Wisconsin

Application December 9, 1938, Serial No. 244,762

14 Claims. (Cl. 37—126)

This invention relates generally to improvements in scraper assemblages of the type adapted to remove and carry quantities of earth from place to place and to dump the loads as desired, and relates more specifically to improvements in the construction and operation of the load confining aprons for road scrapers and the like.

Generally defined, an object of my present invention is to provide an improved scraper apron structure and improved mechanism for manipulating such structures.

It has heretofore been common practice in the manufacture of so-called dig and carry scrapers, to provide the load confining and carrying bowls with front and rear aprons which are cooperable respectively with the bowl to confine the loads therein and to effect removal thereof. The front load confining apron is ordinarily pivotally suspended from the opposite side walls of the bowl and is oscillatable about its suspension pivot, toward and away from the scraper blade carried by the front portion of the bowl bottom, by mechanism such as a hydraulic jack suspended from the front of the scraper frame. In these prior hydraulically actuated front apron assemblages, the plunger of the jack is ordinarily pivotally attached to the swinging forward portions of the front apron and no provision is made for lost motion or relative movement between the apron and the pivot pin, so that when the apron meets an obstruction such as a stump or a boulder, the full force of the impact is conveyed to the jack with possible resulting damage such as bending or breakage of jack parts.

The present invention therefore provides simple and effective means for protecting the front apron manipulating jack of a scraper by providing a lost motion connection which will permit relatively free swinging of this apron relative to the operating jack under certain conditions of operation.

Another specific object of my invention is to provide an improved front apron assemblage for scrapers or the like, which is durable in construction and highly efficient in use.

A further object of the invention is to provide a simplified front apron structure for dig and carry scrapers, which will provide maximum clearance for material entering and leaving the load carrying bowl.

These and other objects of the present invention will be apparent from the following detailed description.

A clear conception of an embodiment of the invention, and of the mode of constructing and of

operating scraper aprons built in accordance with the improvement, may be had by referring to the drawings accompanying and forming a part of this specification, wherein like reference characters designate the same or similar parts in the various views.

Fig. 1 is a part sectional side elevation of a dig and carry scraper assemblage, showing the cutting blade embedded in the ground, the bowl partially loaded, and the front apron lowered;

Fig. 2 is an enlarged part sectional inside or rear view of the front apron alone;

Fig. 3 is a similarly enlarged vertical section through the front apron, taken along the line 3—3 of Fig. 2;

Fig. 4 is a fragmentary part sectional side view of the portion of the scraper adjacent the cutting blade, showing this blade in action and the front apron elevated with the aid of the hoist alone, and

Fig. 5 is a view similar to that of Fig. 4, but showing the front apron additionally elevated to provide maximum space between the apron and the cutting blade.

While the invention has been specifically applied to a particular type of dig and carry scraper assemblage having a load receiving bowl provided with relatively movable front and rear aprons, it is not the intention to thereby unnecessarily restrict the scope of the improvement.

Referring to the drawings, the load receiving and transporting scraper assemblage shown therein comprises in general, a main frame 8 which is swingably and transportably supported at its lower front portion upon a wheeled draft carriage 9, and is provided with rearwardly extending laterally spaced side arms 10 rigidly interconnected at their front and rear ends by transverse beams; a load carrying bowl 11 having parallel side walls 12 rigidly suspended from the side arms 10, and a bottom 13 rigidly connecting the lower extremities of the side walls 12; a cutting blade 14 attached to the front edge of the bowl bottom 13; a front apron 15 having relatively long side arms 16 pivotally suspended from the side walls 12 of the bowl 11 and being operable by means of a hydraulic jack 17 which is pivotally suspended from ears 18 rigidly associated with the front transverse beam of the main frame 8; a rear ejector apron 19 movable longitudinally within the bowl 11 between the side walls 12 and over the bottom 13; actuating levers 20 for the rear apron 19, pivotally suspended from the rear transverse beam of the

55

main frame 8, and being operable by means of a second hydraulic jack 21; an auxiliary frame 22 having its front end pivotally connected to the rear lower portion of the bowl 11, and its rear end pivotally suspended from rear transporting wheels 23; and a third hydraulic jack 24 coacting with the frames 8, 22, to relatively move the same so as to raise and lower the blade 14.

The main frame 8 and bowl 11 are preferably 10 constructed of relatively stiff sheet metal plates, welded or otherwise rigidly interconnected so as to provide a durable assemblage, and the front frame and bowl unit is tiltable upon the draft carriage 9 so as to either position the bowl bottom 13 within the cut as in Figs. 1 and 4, or to 15 elevate the bowl 11 away from the ground. The auxiliary frame 22 which is pivotally connected with the front frame 8 and bowl 11 by means of a transverse pivot pin 25, may likewise be formed 20 of heavy metal plates or beams, and is swingable about the axis of the rear wheels 23 during raising and lowering of the bowl 11 and blade 14. The draft vehicle for propelling the scraper assemblage over the ground, is usually a tractor 25 which is coupled to the front carriage 9; and the pump and control levers for actuating the several jacks 17, 21, 24, are ordinarily carried by the tractor near the operator's seat.

The improved front apron assemblage constituting the present improvement, is shown in detail in Figs. 2 and 3, and the rigid side arms 16 of the apron 15 are pivotally attached to the adjacent side walls 12 of the bowl 13 by means 30 of pivot pins 26. The apron 15 may likewise be constructed of stiff metal plates welded or otherwise firmly united, and the lower portion of this apron is provided with a rearwardly inclined transverse blade 27 which is cooperable with the cutting blade 14 as shown in Fig. 1, in order to 35 confine a load of earth 28 within the bowl 13. The front of the apron 15 has two laterally spaced flanges 29 rigidly attached thereto and projecting forwardly therefrom, and these flanges 29 have aligned arcuate slots 30 therein, the front edges 40 of which are reenforced by metal strips 31. The apron 15 may be additionally reenforced by transverse stiffening plates 32, 33 and by a looped section 34 at the upper portion thereof, so as to 45 provide an extremely rigid and durable apron 50 assemblage.

While the improved apron 15 may be swung about its supporting pins 26 in any suitable manner, I prefer to utilize a hydraulic jack 17 as shown in Figs. 1, 4 and 5. The cylinder 35 of this jack 17 is pivotally suspended from the ears 18 of the main frame 8, by means of trunnions 36; and the piston 37 is slidable within the cylinder 35 and preferably has its outer end provided with a roller pin 38 which is engageable 55 with the slots 30 of the flanges 29. With this cooperation existing between the jack 17 and the front apron 15, the apron will swing downwardly toward closed position as in Fig. 1, by gravity, with the pin 38 normally located in the upper 60 ends of the slots 30, and when the jack 17 is operated to elevate the apron 15, the piston pin 38 will remain in the upper slot ends. If, however, the downward movement of the apron 15 by gravity, is obstructed, and the movement of the piston 37 continues, the pin 38 will continue to move downwardly along the slots 30; and if after the apron 15 has been elevated as far as possible with the aid of the jack 17 as in Fig. 4, and the apron meets an obstruction which tends to further elevate the same, then the slots 30 may move

along the pin 38 to the position shown in Fig. 5.

During normal operation of the improved scraper assemblage, the draft carriage 9 is connected to a suitable traction vehicle, and the circulating pump located on the tractor is normally operating to circulate liquid through the supply reservoir. The hydraulic jacks 17, 21, 24 may then be operated independently of each other to either actuate the front and rear aprons 15, 19, or to elevate or lower the bowl 11 and the scraper 16 blade 14. When the various elements are positioned as shown in Fig. 4, and the assemblage is being moved along the ground, the bowl 11 is being loaded with earth 28 between the side walls 12, and the earth is piled up against the rear 11 apron 19 as it proceeds along the bowl bottom 13. With the blade 14 in cutting position, the bowl bottom 13 is disposed substantially parallel to the plane of cutting, and when the bowl 11 has been sufficiently loaded, the front apron 15 may 20 be lowered to the position shown in Fig. 1, by causing the piston 37 of the jack 17 to move outwardly with respect to the cylinder 35. The front apron 15 then drops by gravity due to its own weight, and if the lower portion of this apron should strike an obstruction and thus prevent gravity lowering of the apron, the piston pin 38 will move downwardly within the slots 30, and if the previous movement of the apron has been insufficient, the pin 38 will engage the lower ends 25 of the slots 30 and will forcibly lower the apron. After the front apron 15 has been thus lowered, the bowl 11 may be elevated and the load of earth 28 may be transported to any suitable 30 dumping place.

When it becomes desirable to elevate the front apron 15 and to dump the load, the hydraulic jack 17 may be manipulated to cause the piston 37 to move upwardly within the cylinder 35. The apron 15 will then be elevated by the jack 17 to 40 the position illustrated in Fig. 4, with the pin 38 in the upper ends of the slots 30. This will open the front of the bowl 11 to normal position. If, however, further elevation of the apron 15 is produced by engagement of the front of the apron with an obstruction and while the scraper is being drawn along the ground, the apron 15 will automatically swing upwardly to the position 45 shown in Fig. 5, without subjecting the hoist 17 to undesirable pressures. Such additional upward movement of the apron 15 is made possible by the slots 30 riding along the roller pin 38. When the obstruction has been passed, the apron 15 will again gravitate to the position shown in Fig. 4 preparatory to subsequent lowering thereof.

From the foregoing detailed description it will be apparent that the lost motion connection between the piston pin 38 and the apron 15, afforded by the tracks or slots 30, will permit the apron to move relatively to the hoist 17 without subjecting the latter to dangerous pressures. The lost motion is effective both during lowering and elevation of the apron 15, and the mechanism for accomplishing this lost motion is obviously extremely simple and has proven highly 55 satisfactory in actual use. It is to be noted that while the tracks or guide slots 30 are curved, they are not generated about the axis of the pivot pins 26 as a center, but they are formed spirally relative to this axis so as to produce a 60 cam action when cooperating with the roller pin 38. This is an important feature of the present invention in producing wide opening of the front apron as indicated by the showings in Figs. 4 and 5. The cam action produced by the 65

special formation of the slots 30 provides for quick enlargement of the opening without changing the position of the jack 17, so that the disposition of these slots is in fact very important.

5 The entire front apron assemblage is very durable and rigid, and the apron is so formed that it will effectively confine the load within the bowl without permitting undesirable spilling. The long arm 16 about which the front apron 15

10 is swingable, also reduces the hydraulic pressure necessary in order to swing this apron about its pivot pins 26, and the improvement is readily applicable to scraper assemblages which have proven unsatisfactory in actual use.

15 It should be understood that it is not desired to limit this invention to the exact details of construction or to the precise mode of operation, herein shown and described, for various modifications within the scope of the claims may occur

20 to persons skilled in the art.

I claim:

1. In a scraper, a transportable frame, a bowl rigidly suspended from said frame and having a front cutting blade, a front apron having side arms pivotally attached to the opposite side walls of said bowl, a jack pivotally suspended from said frame and having a movable member cooperable with said apron to move the latter away from said blade, and slotted flanges carried by said apron and cooperating with said jack member to permit movement of said apron independently of said jack.

2. In a scraper, a bowl having a cutting blade, a front apron swingable toward and away from said blade about an axis, an actuating jack for said apron pivotally suspended from said bowl, and a pin carried by said jack and coacting with a track on said apron, said track being formed to provide a cam action during movement of said

40 pin therealong.

3. In a scraper, a bowl having a cutting blade, a front apron swingable toward and away from said blade about an axis, an actuating jack for said apron pivotally suspended from said bowl, and a roller pin carried by said jack and coacting with a slot on said apron, said slot being disposed spirally relative to said axis.

4. In a scraper, a bowl having a cutting blade, an apron swingable relative to said blade about a fixed axis and having a curved slot disposed spirally of said axis, and a jack for elevating said apron having a pin cooperable with said slot.

5. In a scraper, a bowl having a cutting blade, an apron swingable relative to said blade about an axis and having a curved cam surface disposed spirally of said axis, and a jack having a cylinder pivotally suspended from said bowl and a piston movable in said cylinder and provided with a pin cooperable with said cam surface to elevate said apron.

6. In a scraper, a frame having a cutting blade, an apron movable relative to said blade and having a curved slot therein, an actuating jack for said apron having a cylinder pivotally suspended from said frame and a piston movable within said cylinder toward and away from said apron, and a pin carried by said piston and coacting with said slot.

7. In a scraper, a frame having a cutting blade, an apron swingable relative to said blade about an axis located rearwardly of the latter, said apron having a slot therein curved concavely relative to said axis, an actuating jack for elevating

said apron having a cylinder pivotally suspended from said frame in front of said blade and a piston movable within said cylinder toward and away from said apron, and a roller pin carried by said piston and coacting with said slot.

5

8. In a scraper, a frame having a cutting blade, a front apron swingable about an axis relative to said blade, said apron having a curved slot disposed spirally relative to said axis, an actuating jack for said apron having one member pivotally suspended from said frame and another member movable in said pivoted member toward and away from said apron, and a pin coacting with said slot and with said movable member.

9. In a scraper, a transportable frame having a cutting blade suspended therefrom, a front apron swingable upon said frame about an axis located rearwardly of said blade and being movable toward and away from the blade, said apron having rigid flanges provided with aligned arcuate slots which are concave relative to said axis, and a jack having relatively longitudinally movable members one of which is pivotally suspended from said frame and the other of which has a roller pin coacting with said slots.

15

10. In a scraper, a transportable frame having a cutting blade suspended therefrom, a front apron swingable upon said frame about an axis located rearwardly of said blade and being movable toward and away from the blade, said apron having rigid flanges provided with aligned arcuate slots which are concave relative to said axis, and a jack comprising relatively movable members one of which is swingably suspended from said frame and the other of which is disposed between said flanges and carries an end pin coacting with said slots.

30

11. In a scraper, a transportable frame having a cutting blade and side walls cooperating therewith to form a load receiving bowl, a front apron swingable toward and away from said blade about pivots coacting with said walls, said apron having forwardly projecting flanges provided with aligned arcuate slots, and a jack having relatively movable members one of which is pivotally suspended from said frame and the other of which is movable toward and away from said apron and carries an end pin coacting with said slots.

40

12. In a scraper, a transportable frame having a transverse cutting blade, an apron swingable toward and away from said blade and having a slot curved transversely of its axis of swing, and a jack having relatively movable members one of which is suspended from said frame and the other of which is movable toward and away from said apron and carries a pin coacting with said slot.

50

13. In a scraper, a transportable frame having a fixed transverse cutting blade, an apron swingable toward and away from said blade and having a slot disposed spirally relative to its axis of swing, and a jack having a plunger movable toward and away from said apron and supporting a pin which coacts with said slot.

55

14. In a scraper, a transportable frame having a transverse cutting blade, an apron swingable about an axis toward and away from said blade and having a cam slot disposed spirally relative to said axis, a jack pivotally suspended from said frame and having a plunger movable toward and away from said apron, and a roller pin carried by said plunger and coacting with said slot.
